CLAIM

The ornamental design for a portable gas nozzle trigger accessory, as shown.

DESCRIPTION

FIG. 1 is a perspective view of a portable gas nozzle trigger accessory showing my new design therefor; the broken line drawing depicting a partial view of a gas pump hose and nozzle is for purposes of illustration only and forms no part of my design;

FIG. 2 is a top plan view;

FIG. 3 is a left side elevational view;

FIG. 4 is a front elevational view;

FIG. 5 is a right side elevational view;

FIG. 6 is a rear elevational view; and,

FIG. 7 is a bottom plan view.
